UNITED STATES PATENT OFFICE.

RAY F. SMITH, OF CORTLAND, NEW YORK.

COMPOSITE UPHOLSTERY ROPE OR CORD AND THE METHOD OF MAKING SAME.

Application filed May 18, 1927. Serial No. 192,472.

My invention relates to cords, lines and the like stranded threads or yarns primarily composed of fibrous material, and more particularly pertains to means for reenforcing 5 that class of loosely woven strands which owing to their inherently stretchy nature, have heretofore proven deficient and not altogether serviceable when used under occasional heavy strains for the purposes herein 10 intended.

It is therefore contemplated to fortify upholstery ropes of the conventional all-yarn type against objectionable sagging by resorting to a supplementary embedded ligament 15 or core element extending centrally through the rope filler. This core made up of relatively inextensible material, imparts this unyielding characteristic to the adjoining fibrous filler medium and thereby augments 20 the longitudinal rigidity of the rope structure as a whole. Said ligament is intended to effectively meet the major portion of load that may be carried by my composite rope and thus prevent the surrounding filler body 25 from becoming loaded beyond its limit of resiliency or yield point; it is further preferred to resort to relatively low flexural strength for the core element in order to give ample pliability and obviate retention 30 of any fixed contour when bent transversely.

The object of the present invention is to devise a substantially non-yielding and durable rope capable of taking up considerable lengthwise strain and to provide improved 35 means for economically making composite ropes, especially reenforced upholstered ropes of different sizes, styles and lengths such as find a rather wide application in the field of vehicle robe supporting rails, 40 seat hangers and door grip cords, also in rail ropes for enclosing gangways, stair cases, exhibition spaces and similar decorative or utilitarian purposes. Rope of this kind is commonly cut into comparatively short 45 lengths and suspended between suitable supports or posts; a further object lies in devising effective means for the securement of my non-stretchable core element to such supports whereby undue sag on part of the composite rope may be checked or retarded even 50 when subjected to abnormal usage or strain.

A still further object is to provide for building up a fibrous filler medium adapted to neatly conceal and grip said reenforcing 55 core, and in turn to surround this smoothly rounded filler contour with a decorative

outer sheath that serves to adorn my composite rope. In addition, means have been devised for neatly trimming the ends of such rope sections with appropriate terminal fittings that are securely bonded to the component rope elements and adapted to transmit the full rated load without diminution 60 of rope capacity.

An improved rope of the indicated character lends itself to many uses, and as exemplified by the cited robe rail for automobiles, my reenforced rope when hung and transversely loaded with lap robes or heavy wearing apparel is still capable of withstanding 65 the resultant strain without suffering a pernicious set or permanent stretch. Robe rails are not infrequently subjected to unusual strains and especially when fashioned from conventional twisted rope, they tend to 70 stretch progressively under repeated overloads. Eventually the resulting sag of such all-yarn ropes is likely to become augmented to such extent that the suspended garments are no longer properly held off the 75 closely adjacent car floor and owing to inward crowding, said garments soon become badly mussed. It will also be apparent that an abnormally stretched or drawn condition of the robe rail detracts appreciably from 80 the trim appearance of the car interior.

Embodied herein are other features of structure and organization designed to facilitate the economical fabrication of such composite ropes on a large scale production, all 85 of which will be set forth in further detail hereinafter. Reference is had to the accompanying one sheet of drawings as an illustrative embodiment of my invention; like characters of reference indicate like parts in 90 the several views and in which drawing:

Fig. 1 is a side elevation showing my inextensible rope applied as a robe rail located at the back of an automobile seat, the opposite rope ends being for convenience 95 shown as equipit with two different styles of bracket attachments.

Fig. 2 is a broken perspective view of one type of core element that may be embedded within the filler medium of a robe rail such 100 as shown in Fig. 1.

Fig. 3 represents an enlarged detail of the left-hand terminal piece as taken along line 3-3 of Fig. 1 while Fig. 4 is a similar detail of the modified right-hand piece taken 105 along line 4-4.

Fig. 5 depicts a series of linked or inter-

connected core elements of the type indicated in Fig. 2 and which chain of links may be covered with a fibrous filler medium by means of a continuous laying process.

5 Fig. 6 shows still another style of rope terminal fitting which likewise permits the reenforced rope to be fabricated continuously but differs somewhat from the showing of Fig. 5 in that a perforated band or tape of 10 relatively thin metal is here utilized as the core elements, the terminal fittings being anchored thereto after cutting the rope into finite lengths.

Fig. 7 is a transverse section of said core 15 tape as taken along line 7—7 of Fig. 6.

Fig. 8 shows a fragmentary sectional view similar to Fig. 4 except that a crocheted fabric hood is here resorted to for trimming the rope end.

20 Referring first to Fig. 1, the numeral 1 designates in its entirety a composite rope means of any desired length of which the respective end portions may be attached to support brackets such as 2 and 3. In the 25 chosen embodiment, said rope supports are shown applied to the rear of an automobile front seat and serving to suspend a robe rail of the flexible cord type.

The substance of the present invention 30 has to do more largely with a longitudinally disposed non-stretchable core reenforcing element denoted as a whole by 4, and which is preferably embedded near the center region of its surrounding stretchable filler or body 35 medium 5. Said core may comprise one or more end to end linked elements of which one such may be formed into a relatively flexible cable section interposed between suitable terminal pieces as indicated in Fig. 40 2. Said intermediate section such as 4^a may be made up of a plurality of metallic stranded wires, flat tape or the like ligament possessing a sufficiently high coefficient of rigidity to enable a suspended or otherwise 45 hung cable of this kind to carry its anticipated load without appreciable elongation or permanent stretch.

The cross-sectional area of such cable means 4^a is preferably kept small relative to 50 the exterior of the pliable filler 5 in order not to unduly stiffen the rope transversely at least in one direction and thus afford sufficient pliability to assume a graceful catenary or chain-like curvature when looped or 55 freely suspended between two closely spaced support members such as the brackets 2 and 3 of Fig. 1.

In the particular core embodiment shown 60 in Fig. 2, relatively stiff terminal pieces are provided to reenforce the end regions of the flexible cable 4A and said pieces are here fashioned into short metallic extension straps or keepers 7 and 8. Each such strap 65 may be provided with a series of spaced holes therethrough such as 7A, 7B, and 7C,

and the respective ends of the cable core portion 4A may be secured to said complementary straps in any suitable manner, for instance by the eye end means having the return loop end secured upon itself by tubular clamps 9 as indicated. The purpose of said straps is to provide for a manipulative member adapted to reenforce the somewhat fragile stranded cable 4A and it will be observed that said straps together with the intermediate cable section are intended to form an embedded ligament that affords a continuous metallic tie connection capable of being firmly anchored to the respective rope end supports.

In order to facilitate the manufacture of my composite rope, a plurality of core elements similar to those shown in Fig. 2 and of any predetermined sectional length such as L, L', etc., may be coupled together by 85 means of detachable core links (designated as 10, 10' etc.) to form a chain of linked members in the manner indicated in Fig. 5 but as will appear hereinafter, such a continuous core may also be made up in other 90 ways. The formation of a relatively long core means that possesses the described characteristics, constitutes the first step in my method of making reenforced ropes.

A core chain or other virtually continuous 95 core medium having an indefinite length but at least as long as the shortest desired single unit measurement L, L', etc., may most readily be carried up and made to feed through the former of a suitable braiding machine 100 or the like. The second step in my method consists in providing for braiding, or otherwise laying a filler 5 upon and lengthwise of the aforesaid linked core elements, it being understood that the term "laying of the 105 filler" is herein used in its broadest sense to include any suitable method adapted to pack the filler yarn around the core member. This filler may comprise a plurality of comparatively loosely woven superimposed layers of 110 yarn or other similar filler body material, preferably of an inherently pliable fibrous and stretchy character such as will freely accommodate itself to any sharp deflection on part of the more rigid core member. The 115 purpose of said body medium is to provide for an enlarged and substantially uniform periphery about said intermediate ligaments 4A together with the adjoined straps 7 and 8 and thereby form a suitable smooth foundation for the finishing covering 5A. This filler 5 further provides for a protective cushioning medium between said outer sheath and the concealed core element; it not only maintains initial fullness but keeps said sheath in a perfect sleek condition and prevents collapse or peripheral distortion thereof.

When the cited braiding operation is used 125 to lay the rope filler, the partially completed 130

rope may be reeled between successive layers and this operation repeated until the desired body thickness has been reached; if desired this operation may also be effected by running my rope ligament through a series of machines, each of which braids one or more such layers. It is emphasized that my virtually endless core link method greatly expedites and otherwise effectively reduces the cost of making such composite ropes. In resorting to the type of enlarged ends for the ligament as shown in Figs. 2 or 5, the several intermediate reduced core portions as 4A, may first be built up until they assume an essentially uniform perimeter with respect to said ends, after which it is expedient to apply the remaining filler layers evenly along the entire length of the linked core elements. Obviously, substantially the same result may be obtained by other well known means, such as wrapping strips of fabric or sheets of paper around said core elements or by laying the core binding strands in a twisted or plied fashion other than braiding. The outer or last of such filler layers is here shown as worked up into a seamless finishing sheath 5A, and this is preferably woven from variously colored plied or braided yarns such as rayon or the like, adapted to decorate and enhance the salability of my upholstery rope. As applied to automobile robe rail purposes, it is advantageous to finish such textile covering into an anti-slip or friction surface adapted to prevent the suspended apparel from slipping off while subjected to jolting or car vibration.

Regarding the intermediate strap hole 7B, one or more such may be utilized to receive suitable pronged cleats or filler bonds such as 12, which securement obviates slipping of the filler along the core ligament. As shown in Fig. 3, the rivet cleat 12 may comprise an L shaped staple that is driven through said hole 7B as indicated in dotted lines, whereupon the projecting unbent leg thereof may be clinched down in place as shown in full lines for establishing a tighter grip between the strap 7 and its surrounding filler 5. This cleat is preferably inserted prior to weaving the finishing sheath 5A so as not to deface the exterior of the rope; any suitable filler gripping means projecting outwardly from the core element will answer said interlocking purposes and any such bond may be applied either before or after wrapping the filler about the core element.

As a third step in my method of making said reenforced rope, this is now cut into any desired fixed length to meet requirements. In the event a linked core should be used as indicated in Fig. 5, the severing of my rope of indefinite length is intended to occur in the region of the separable core links 10, 10', etc., which links may thereupon be discarded. Said relatively long rope is thereby divided

into a series of unit or sectional ropes each having a predetermined but selective length L, L', etc., and it now merely remains to trim the complementary rope ends in one of several alternative ways.

Referring first to Fig. 3, the keeper strap 7 is here shown as a flat terminal piece having its surrounding filler trimmed back to partially expose the free strap end for attachment purposes. An apertured cap or ferrule such as 6 may be sprung over and cemented to the end of the sheath 5A so as to incase and prevent the rope end from becoming frayed or unraveled; if preferred, the same end may be attained by trimming the filler end by means of a cord binding. The exposed projection of the strap 7 may thereupon be fitted into the socket 2A of the support bracket 2 and a wedge pin 2B entered and driven through the outermost strap hole 7C to interlock and firmly anchor the rope core into said bracket. Either of such robe rail fastenings may however be made detachable to facilitate placing garments thereon.

The fourth step in my method resides in providing for suitably anchoring the rope ends to enable said core ligament to give better support to the surrounding fibrous filler medium but this particular step is optional and does not represent an indispensable feature in the making of my composite rope.

Referring now to Fig. 4, it will be seen that this style of terminal strap 8 is essentially similar to the previously described strap 7, except that the aperture 7A is now replaced by a bent up eye end 8C; this alternative method may in turn engage the endless link or ring 3B as mounted through the hook 3A of the modified bracket 3. A ferrule 6 may again be resorted to and this is here provided with an apertured cap portion adapted to slip over the strap eye end 8C.

Regarding a further modification as shown in Fig. 6, a metal tape or other strip of non-stretchable ligament 4A' is indicated which may be provided with a series of closely spaced perforations 7C' to serve as the integral equivalent of the aforesaid core chain links, and a filler medium 5 together with a finishing sheath 5A may again be woven thereon in the manner previously described. Said tape is preferably kept amply long while passing through the braiding machine to allow of fabricating the rope in easily workable stock lengths which may subsequently be cut off into any shorter lengths without having to predetermine the desired finite lengths.

The filler adjacent to the respective rope ends may then be cut back a short distance with respect to the severed tape ends 4A'' so as to expose one of the perforations such

as 7C". In this instance, it may also be expedient to alter the support bracket somewhat and provide one such designated as 11, having a tubular socket or housing portion 11A equipt with an inwardly disposed flange 11B and an aperture 11C therefor adapted to snugly embrace the rope sheath 5A.

When resorting to the style of terminal that is shown in Fig. 6, it is preferred to 10 pass the rope end through the bracket aperture 11C and apply a slightly modified cap or ferrule such as 6A which is provided with an outwardly flared flange 6A' adapted to abut the reversed flange 11B in the manner 15 shown. A bent up pin 2B' engaging the tape aperture 7C" serves to lock the ligament into the bracket 11. Should it be desired to bond said tape 4A' into the filler 5, this may be accomplished by the use of one or more cleats 20 such as 12A which are here concealed within the bracket housing and intended to pass through one of said tape perforations. Owing to the pliable nature of my composite rope, its end may be drawn through the aperture 25 11C to more conveniently secure the described terminal members in place and whereupon the fitted rope may readily be sprung back into its indicated operative position.

30 As a further alternative for trimming the rope filler ends, Fig. 8 shows a fabric hood 6B that is substantially equivalent to the metal ferrule 6 of Fig. 4, said hood being adjoined upon the end of cover 5A in any 35 suitable manner, and again apertured at 8A' to permit the shank of the strap to pass therethrough.

From the foregoing it will be seen that I have provided for a novel and effective 40 method for the rapid production of a composite rope and one embodying either an interconnected or continuous inextensible core ligament that extends longitudinally through the surrounding resilient filler medium and serves as an effective reenforcement and protection for the latter. Said 45 filler may be made up of any fibrous substances having an inherently stretchy and pliable character and which of itself does not possess sufficient rigidity to sustain 50 heavy strains without undergoing an ultimate permanent sag; as such it provides for a suitable cushioning body and takes out any unevenness in the contour of the core element. Furthermore, my well-rounded 55 rope structure is finished with a neat seamless outer covering to make it entirely suitable as applied to fine upholstery or other trimming purposes. In addition, my incorporated ligament is kept transversely flexible and because this core is anchored directly to the rope support, it is adapted to 60 carry the major portion of any reasonable load that may be exerted thereon, all without abnormal elongation or allowing undue 65

strain to fall upon the stretchable filler body or covering therefor. As a result, there has been achieved an ornamental composite rope capable of retaining its shape and without tendency to permanently stretch the loosely woven filler medium even under adverse load conditions or jeopardize the initial looseness 70 of knit and fluffy luster of my sheath covering.

While specific embodiments of my invention have been set forth in detail, it is to be understood that the herein described structures may readily be modified to meet differing conditions of use and manufacture, such for instance as the making up of my composite rope in predetermined short lengths rather than in the indicated endless fashion, and that various changes in the details of my method may be resorted to, all without departing from the spirit and 80 scope of my invention as more particularly pointed out in the appended claims.

I claim—

1. The method of making flexible composite ropes or the like comprising a core 90 ligament means that is substantially inextensible longitudinally but kept flexible transversely and which ligament is embedded lengthwise of a relatively stretchy filler medium, said method consisting in the 95 following steps, viz: firstly, forming a core ligament means comprising a series of finite cable lengths each having their respective ends reenforced by a relatively rigid keeper strap and which straps are initially coupled 100 together into an indefinite length; secondly, repeatedly carrying said ligament through a braiding machine or machines to lay thereon a series of superimposed layers of braided 105 yarn strands adapted to build up a pliable filler body; and lastly, severing to divide said composite rope into finite sectional lengths each provided with reenforced ends.

2. The method of making flexible composite ropes or the like comprising a core 110 ligament means that is substantially inextensible longitudinally but kept flexible transversely and which ligament is embedded lengthwise of a relatively stretchy 115 filler medium, said method consisting in the following steps, viz: firstly, forming a continuous core ligament means having enlarged 120 reenforced end portions that are adjoined to a relatively flexible intermediate portion; and lastly, laying fibrous strands between 125 said enlarged end portions until said ligament assumes a substantially even size and thereupon superimposing layers of such strands extending throughout the length of said ligament to build up a filler body of substantially uniform periphery embracing a cross-section area materially larger than that of the core ligament.

3. The method of making flexible composite ropes or the like comprising a core 130

ligament means that is substantially inextensible longitudinally but kept flexible transversely and which ligament is embedded lengthwise of a relatively stretchy 5 filler medium, said method consisting in the following steps, viz: firstly, forming a core ligament means comprising a flexible cable length having each of its ends reenforced by a relatively rigid keeper strap; secondly, 10 laying thereon a filler body composed of fibrous strands of a different material from that used in forming said ligament and which filler is bonded to said ligament to prevent slippage therebetween, and lastly, 15 braiding a tubular finishing cover over both said filler body and the aforesaid bonding means.

4. The method of making flexible composite ropes or the like comprising a core 20 ligament means that is substantially inextensible longitudinally but kept flexible transversely and which ligament is embedded lengthwise of a relatively stretchy filler medium, said method consisting in the 25 following steps, viz: firstly, forming a core ligament means comprising a flexible cable length having each of its ends reenforced by a relatively rigid keeper strap provided with a plurality of spaced perforations; and 30 lastly, laying thereon a body of braided fibrous filler strands adapted to accommodate itself to lateral flexure on part of said ligament and bonding said body to the ligament by fully concealed means of the 35 clinched staple type entered through one or more of the aforesaid spaced perforations.

5. The method of making flexible composite ropes or the like adapted for suspension between support means and which rope 40 comprises a core ligament kept substantially inextensible longitudinally but flexible transversely and which ligament is embedded lengthwise of a relatively stretchy filler medium, said method consisting in the 45 following steps, viz: firstly, forming a core ligament means comprising a flexible cable length having each of its ends reenforced by an apertured relatively rigid keeper strap; secondly, laying thereon a pliable filler body 50 composed of braided fibrous strands; and lastly, anchoring said straps directly to the rope support by means of the respective strap apertures.

6. The method of making flexible composite ropes or the like adapted for securement to support means and which rope comprises a core ligament kept substantially inextensible longitudinally but flexible transversely and which ligament is embedded 55 lengthwise of a relatively stretchy filler medium, said method consisting in the following steps, viz: firstly, forming a core ligament means comprising a series of finite cable lengths each having their respective ends reenforced by a keeper strap and which 60

straps are initially coupled together into an indefinite length; secondly, laying thereon a pliable filler body composed of fibrous strands; thirdly, severing to divide said composite rope into finite sectional lengths each 70 provided with reenforced ends; and lastly, trimming back a terminal portion of one such length to expose the outermost severed ligament end portion and prepare the same for anchorage to the rope support means. 75

7. The method of making flexible composite ropes or the like adapted for securement to support means and which rope comprises a core ligament kept substantially inextensible longitudinally but flexible transversely and which ligament is embedded lengthwise of a relatively stretchy filler medium, said method consisting in the following steps, viz: firstly, forming a core ligament means comprising a flexible cable 80 length having each of its ends reenforced by a relatively rigid keeper strap provided with a plurality of spaced perforations; secondly, laying thereon a pliable filler body composed of fibrous strands and bonding said body to the ligament of staple means entered through one of the intermediately disposed perforations of each strap; and lastly, trimming back the respective filler body ends to expose the respective terminal 85 perforations for interlocked anchorage to the rope support means. 90

8. The method of making flexible composite ropes or the like adapted for securement to support means and which rope comprises a core ligament kept substantially inextensible longitudinally but flexible transversely and which ligament is embedded lengthwise of a relatively stretchy filler medium, said method consisting in the following steps, viz: firstly, forming a core ligament means comprising a series of finite cable lengths each having their respective ends reenforced by a relatively rigid keeper strap and which straps are initially coupled together into an indefinite length; secondly, laying thereon a pliable filler body composed of fibrous strands; thirdly, severing said composite rope into finite sectional lengths; and lastly, trimming back the end portions of one such filler body length to expose its complementary ligament terminals and incasing each of such filler body 100 ends within an apertured ferrule-like hood through which the respective terminal projects for anchorage to the rope support means. 105

9. The method of making flexible composite ropes or the like adapted for securement to metal support means and which rope comprises a core ligament kept substantially inextensible longitudinally but flexible transversely and which ligament is embedded lengthwise of a relatively stretchy 110 filler medium, said method consisting in the 115

following steps, viz: firstly, forming a definite length of metallic ligament means comprising a flexible cable length having each of its ends reenforced by a relatively rigid keeper strap; secondly, laying thereon a pliable filler body composed of fibrous strands; and lastly, attaching the respective ligament terminals to spaced rope support means to constitute a continuous inextensible and direct metal tie connection therebetween adapted to take up the major portion of rope loading and obviate stretching of the filler medium beyond its yield point.

10. The method of making flexible composite ropes or the like adapted for securement to support means and which rope comprises a core ligament kept substantially inextensible longitudinally but flexible transversely and which ligament is embedded lengthwise of a relatively stretchy filler

medium, said method consisting in the following steps, viz: firstly, forming a continuous metallic ligament means of finite length comprising an intermediary flexible cable portion whose ends are adjoined to keeper strap-like members of an enlarged cross-sectional area adapted to reenforce the cable terminals for attachment purposes; secondly, laying thereon a pliable filler body composed of fibrous strands and which built-up body provides for smooth covering sheath of substantially uniform periphery adapted to conceal the innermost end portions of said interconnected straps; and lastly, preparing the terminal portions of said straps for securement to the rope support means.

In testimony whereof, I have herewith set my hand this 12th day of May, 1927.

RAY F. SMITH.
